DESIGN FOR A FOOD CONTAINER UNIT

Lewis H. Scurlock, Chicago, Ill.

Application March 2, 1934, Serial No. 50,920

Term of patent 14 years

To all whom it may concern:

Be it known that I, Lewis H. Scurlock, a citizen of the United States, and resident of Chicago, in the county of Cook and State of Illinois, have invented a new, original, and ornamental Design for a Food Container Unit, of which the following is a specification, reference being had to the accompanying drawing, forming a part thereof:

Fig. 1 is a plan view of a food container unit showing the new and ornamental design.

Fig. 2 is a front elevation of said food container unit.

Fig. 3 is a vertical transverse section of one of the five separate covers of said food container unit.

The device of my design comprises the several container elements and covers therefor shown in solid black lines in the drawing, combined with a base shown in dotted lines. The dominant features of the design are shown in the solid black lines. The ornamental feature of the design comprises the particular arrangement of the containers and covers as shown.

I claim:

The ornamental design for a food container unit, as shown and described.

LEWIS H. SCURLOCK.
